UNITED STATES PATENT OFFICE.

HUGH SWINTON McGILLIVRAY, OF CHARLESTON, SOUTH CAROLINA.

DESIGN FOR A DOOR KNOCKER.

Application filed April 16, 1928. Serial No. 26,329. Term of patent 7 years.

To all whom it may concern:

Be it known that I, HUGH SWINTON McGILLIVRAY, a citizen of the United States, residing at Charleston, in the county of Charleston and State of South Carolina, have invented a new, original, and ornamental Design for Door Knockers, of which the following is a specification, reference being had to the accompanying drawing, forming part thereof.

Fig. 1 is a front view of a door-knocker, showing my new design. Fig. 2 is a side view of the same.

I claim:

The ornamental design for a door-knocker, as shown.

HUGH SWINTON McGILLIVRAY.
